UNITED STATES PATENT OFFICE.

JOHN B. DAMAS AND JOSEPH FRANCIS, OF SONORA, CALIFORNIA.

ROCK-DRILLING MACHINE.

No. 896,518.

Specification of Letters Patent. Patented Aug. 18, 1908.

Application filed September 20, 1907. Serial No. 393,797.

To all whom it may concern:

Be it known that we, JOHN B. DAMAS and JOSEPH FRANCIS, both citizens of the United States, residing at Sonora, in the county of 5 Tuolumne and State of California, have invented new and useful Improvements in Rock-Drilling Machines, of which the following is a specification.

Our invention relates to improvements in 10 rock drilling machines, and consists in a means by which exhaust air from the reciprocating engine is utilized to blow the cuttings away from the cutting bits or tool as the work progresses.

15 It also comprises details of construction which will be more fully explained by reference to the accompanying drawings, in which—

Figure 1 is a longitudinal section of a drill 20 showing our invention. Fig. 2 is a similar view in another position. Fig. 3 is a view showing end of drill.

We have here shown our invention applied 25 to a drilling engine which was patented to John B. Damas, September 8, 1903, #738,416, but it will be understood that it may be applied to any similarly impelled engine.

As herein shown, A is a cylinder, and B a double headed piston adapted to reciprocate 30 therein when impelled by any medium under pressure. Air is usually employed in this class of engines.

35 3 is a slide valve movable upon a valve seat, having the customary chambers connecting with ports 4 leading to the ends of the cylinder, and to a central exhaust chamber 5, through which the air from the cylinder is discharged by the movements of the valve after its work in the cylinder is completed. The valve 3 may be reciprocated in 40 unison with the movements of the piston, in any suitable manner. In the present illustration it is actuated by a T-shaped lever 6 so fulcrumed as to be actuated by the reciprocations of the piston, and having one arm made to engage the valve. The piston-rod 7 is hollow, as shown at 8, and connects through the hollow chuck 9 with the hollow drill shank 10.

45 50 11 are holes extending from the hole in the piston-rod, so as to communicate with the exhaust chamber.

The reciprocations of the engine piston are communicated to the drill, which continually cuts away the rock, and to prevent these cuttings from clogging and impeding the drill in its work, the air blast admitted into the piston and drill shank, acts to blow the cuttings out of the hole in the rock, and thus leave the face against which the drill acts, 60 substantially clean and free.

During the reciprocations of the piston within the cylinder, the T-shaped lever has its ends alternately lifted by the larger ends of the piston, and the opposite end which engages the valve 3, causes said valve to slide upon its seat so as to open communication alternately between the pressure chamber and the cylinder ends, and also between the opposite ends of the cylinder and the exhaust chamber 5. This chamber communicates with the cylinder at such a point that the piston ends always maintain the chamber closed with relation to the ends of the cylinder, in which the elastic medium 75 operates. The holes 11 passing through the piston, and into the piston rod 7, which is fixed in the piston, will thus admit the exhaust fluid at each impulse; and this fluid passes through the piston rod, and drill shank as previously described.

Having thus described our invention, what we claim and desire to secure by Letters Patent is—

1. In an elastic fluid impelled engine, a cylinder, a piston having heads at opposite ends fitting said cylinder, and an intermediate connection of smaller diameter, a slide valve with ports adapted to connect with opposite ends of the cylinder, and alternately admit and exhaust an impelling fluid, an exhaust receiving chamber communicating with the cylinder between the piston heads, a hollow piston rod fixed to the piston, openings through the piston connecting the exhaust chamber with the interior of the piston rod, and a hollow drill shank in open communication with the interior of the piston rod.

2. In an elastic fluid impelled engine, a cylinder, a piston reciprocable therein, a hollow piston-rod and hollow drill with a connecting chuck, a slide valve, and means by which it is reciprocated in unison with the

piston, with inlet and exhaust ports controlled thereby, and an exhaust receiving chamber, said piston having passages connecting the exhaust chamber with the interior of the piston-rod and through the drill to the cutting edge.

In testimony whereof we have hereunto

set our hands in presence of two subscribing witnesses.

JOHN B. DAMAS.
JOSEPH FRANCIS.
